GAS ABSORPTION PIPETTE

Maryan P. Matuszak, Pittsburgh, Pa., assignor to
 Fisher Scientific Company, Pittsburgh, Pa., a
 corporation of Pennsylvania

Application October 23, 1933, Serial No. 694,763

9 Claims. (Cl. 23—292)

This invention relates to pipettes used in gas analysis, and more particularly to bubbling gas absorption pipettes of the type having automatic control valves and which are used in gas analysis apparatus of the well known Orsat type.

Heretofore such pipettes commonly have been provided with valves made hollow so that they might float in the liquid absorbent, and it has also been necessary to provide special means for guiding the float valve so that it would seat itself properly. This has usually taken the form of one or more projections from either the upper or the lower side of the float valve. In addition, because of the floating character of the valve, one or more projections, or baffles, from the inside upper wall of the valve chamber, have been necessary to further keep the valve in place or to prevent its entering and closing off the inlet to the valve chamber. Furthermore, the effective or operative portions of the float valves heretofore used in pipettes of this type have been of an essentially conical shape such as to present a considerable region of contact when seated on the valve seat, whereby it not infrequently happened, despite claims to the contrary, that the valve froze or stuck fast in its seat. This undesirable effect has been aggravated by having the valve seat also of an essentially conical or a cup-shaped construction, which has offered some resistance to the free movement of the valve.

Consequently, such prior pipettes have suffered from various disadvantages, chief among which has been the fragility due to the structural features just mentioned. Their fragility has been enhanced also by the fact that the bubbling tube which conducts the gas into the absorbent has been connected to the valve chamber at a point located above the valve seat, and passed thence as an exterior tube, paralleling the valve chamber, to a point located below the valve seat, at which latter point it entered the absorption part of the pipette. This construction has not only made the pipette very fragile and easily broken but has detracted from the appearance of the pipette, because of its unsymmetrical design, and has decreased the effective or operative height of the pipette, because of the space required by the exteriorly located valve chamber and gas conducting tube and their common juncture.

Major objects of this invention are to provide improved gas absorption pipettes, which are simple, sturdier than those available heretofore, and which eliminate or minimize the disadvantages of the pipettes known in the art.

The invention may be described in connection with the accompanying drawing, which is a vertical or longitudinal section through the center of the preferred embodiment of the invention.

The pipette comprises a pair of containers connected at their lower ends to act as absorption and expansion elements, the absorption element being provided at its upper end with a gas inlet connection, preferably tubular. These containers may be separate tubular members connected at their bottoms by an integral tube, as in the conventional forms commonly used with Orsat apparatus, but it is preferred to arrange them within one another in a manner described herein-after.

In accordance with the invention the absorption container is provided adjacent its upper end with means, such as a partition wall integral with the container, dividing the container interiorly into a valve chamber and an absorption chamber. The valve chamber wall is provided with a valve opening adapted to act as a valve seat for a valve member which is guided within the valve chamber toward and from the seat thus provided. Although various forms of valve member may be used, it is preferred to use spherical valves, and most advantageously truly spherical glass balls, for reasons presently to be pointed out. Most advantageously the bubbling, or gas-conducting, tube commonly embodied in such a pipette lies wholly within the pipette, extending, for example, from the valve chamber downwardly within and to the lower portion of the absorption chamber.

Having reference now to the drawing, the embodiment shown comprises an absorption container 1 and an expansion container 2, each of generally cylindrical cross section. The upper end of the absorption container is provided with a projection of reduced cross section, such as the tube-like projection 1a, to which there is connected a gas inlet connection, such as a capillary tube 3. The gas inlet tube may be arranged in various manners, but preferably it is aligned with projection 1a, as shown, to be central to the container. The container is divided into a valve chamber 4 and an absorption chamber 5 by a partition or valve chamber wall 6 interiorly of and integral with the container. The valve wall is provided with an opening 7 arranged below and centrally of the projection 1a, and thus in the form shown centrally of gas inlet 3. The upper side of opening 7 is shaped to provide a seat for a valve member 8, most suitably by shaping the wall as shown in the drawing to form a short

tubular extension $7a$ of opening 7 . Valve member 8 advantageously is non-floating, suitably in the form of a spherically true non-floating ball, e. g., of solid glass.

5 The upper part of the valve chamber, i. e., projection $1a$ in the form shown, is of such form and size and so positioned with respect to the valve seat that ball 8 is retained for and guided in its movement toward and from its seat in opening 7 , and so that it can not escape laterally into the sides or bottom of the valve chamber.

10 In the preferred embodiment of the invention the lower portion of container 1 is of reduced cross-sectional area, which confers important advantages presently described. Extending downwardly into the lower portion from the lower end of wall 6 is a tube 9 which terminates in a hollow perforated sphere 10 , to provide a bubbling tube.

15 Expansion chamber 2 surrounds and totally encloses the lower, reduced section portion of the absorption chamber, as shown in the drawing. The two containers are connected at their lower ends by perforations, or notches 11 , formed at the lower end of container 1 .

20 It will be noted that the invention provides a pipette of simple and sturdy design since the valve chamber, valve seat, and bubbling tube are not only integral with the absorption vessel of the pipette, but are entirely within and surrounded by it, so that no fragile exterior tube or valve chamber is present. Features of the 25 invention of particular importance are that the valve itself is the least fragile part of the pipette, as it is a simple solid ball, it does not require any accompanying retarding baffle, as it does not float, and it has no fragile guiding projections and 30 needs none as it can be seated in any position whatever.

35 Moreover, the valve makes contact with the 40 valve seat in a very narrow and but slightly inclined zone of contact and hence is not subject to sticking or freezing. Furthermore, the valve seat consists of the end of a short upwardly projecting tube and is not cup-shaped, so that it does not offer any resistance to the free movement of 45 the valve. Finally, it will be noted that the appearance of the pipette is neat, because of the general symmetry of the design, and that the 50 effective or operative height of the pipette has not been appreciably decreased by the inclusion of the valve feature.

55 In the practice of this invention the liquid absorbent in the absorption container 1 is drawn up to a point above the valve chamber in a manner well known to those skilled in the art. The sample of gas is then propelled into the pipette through the capillary 3 at the top of the pipette. The liquid absorbent is thereby forced from the valve chamber 4 through the bubbling tube 9 and 60 is followed by the gas, which issues in the form of bubbles from the perforations in the hollow sphere 10 . The gas can not pass through the opening of the valve seat 7 because this opening is closed by the ball valve 8 . The bubbles of 65 gas rise through and collect above the absorbent in chamber 5 , the absorbent being correspondingly forced into the expansion chamber formed by container 2 . A plug of liquid remains in the short tube whose upper end comprises the valve seat 7 .

70 When it is desired to discharge the pipette of the residual unabsorbed gas, a slight decrease in pressure is created in valve chamber 4 , in a manner familiar to those skilled in the art, as by the lowering of a leveling bulb connected to a gas 75 burette, not shown. This causes the gas to rush

up through the opening of the valve seat 7 , pushing up and aside the ball valve 8 and the plug or liquid beneath it. The ball valve, wet by the plug of liquid, sticks to the adjacent side of the upper part of the valve chamber, by virtue of the 80 surface tension exerted by the liquid that wets it and the region surrounding the point of contact, so that it rests on the rim of and partly overhangs the valve seat. This permits the gas to escape from the pipette without causing the ball to rattle or vibrate or interfere in any other way with the upward passage of the gas. When the gas is 85 discharged from the pipette the liquid absorbent rises above the ball valve, completely surrounding it and removing the surface tension effect mentioned above, whereupon the ball valve falls back into the valve seat and the pipette is ready for 90 the next passage of gas.

An addition feature wherein the embodiment of this invention differs from and is superior 95 to previous gas absorption pipettes used in gas analysis apparatus of the well known Orsat type lies in the difference in the cross section of the upper and lower regions of the absorption container 1 of the pipette. The upper region of 100 container 1 is larger, advantageously about 50 mm., and the lower portion is smaller, advantageously about 27 mm., in diameter, than the absorption parts of other pipettes, which have uniform diameters ranging from 32 to 42 millimeters. 105 This novel arrangement offers two distinct advantages. The first of these is that the expanded upper portion permits the collection of the gas that has bubbled through the absorbent, during the passage of the gas sample, without reducing 110 the length of the effective or operative column of absorbent as much as in pipettes having this portion of a smaller diameter. The second advantage is that the lower narrow portion causes the liquid absorbent to flow downward with greater 115 velocity than in pipettes having this part of greater diameter, thus appreciably slowing down the upward rise of the gas bubbles. Because of these two advantages the time of contact of the 120 gas bubbles with the liquid is made longer, thus increasing the efficiency of absorption, without increasing the time required for a passage of the 125 gas sample.

According to the provisions of the patent statutes, I have explained the construction and mode 130 of operation of my invention, and have illustrated and described what I now consider its best embodiment. However, I desire to have it understood that, within the scope of the appended 135 claims, the invention may be practiced otherwise than as specifically illustrated and described.

I claim:

1. In a gas absorption pipette comprising a pair of containers connected at their lower ends, the combination with one of said containers of a gas 140 inlet tube connected to the upper end of the container, a partition wall provided with a pair of openings lying within the container adjacent its upper end and dividing the container internally into an upper valve chamber and a lower absorption chamber, a short tube projecting upwardly into the valve chamber from one of said openings with its upper extended end concentric to said valve chamber and forming a valve seat, a gas 145 conducting, or bubbling, tube extending downwardly from the other of said openings into the lower part of said absorption chamber, and a valve member disposed in said valve chamber for cooperation with said valve seat.

2. A gas absorption pipette comprising a pair 150

- of containers connected at their lower ends, one of said containers having its upper end of generally conical form and having a gas inlet tube connected to the upper end thereof, a partition 5 wall lying within the container adjacent its upper end and provided with a pair of openings, said partition wall dividing the container internally into an upper valve chamber and a lower absorption chamber, a short tube projecting upwardly 10 into the valve chamber from one of said openings with its upper end concentric to said valve chamber and forming a valve seat, a spherically true ball valve member disposed in said valve chamber for cooperation with said seat, and a gas 15 conducting, or bubbling, tube extending downwardly from the other of said openings into the lower part of said absorption chamber, said tube lying wholly within the container.
3. A gas absorption pipette comprising a pair 20 of containers connected at their lower ends, one of said containers having its upper end of generally conical form and having a gas inlet tube connected to the upper end thereof, a partition wall lying within the container adjacent its upper end, said partition wall being provided with a pair of openings and dividing the container internally into an upper valve chamber and a lower absorption chamber, a short tube projecting upwardly into the valve chamber from one 25 of said openings with its upper end concentric to said valve chamber and forming a valve seat, a solid glass spherically true ball valve member disposed in said valve chamber for cooperation with said seat, and a gas conducting, or bubbling, tube extending downwardly from the other of 30 said openings into the lower part of said absorption chamber, said short tube and said bubbling tube lying wholly within said container.
4. A gas absorption pipette comprising an absorption container and an expansion container 35 connected at their lower ends, said absorption container having a gas inlet tube connected to its upper end, a partition wall within the absorption container adjacent its upper end, said wall being provided with a pair of openings and dividing the container internally into an upper valve chamber and a lower absorption chamber, a short tube projecting upwardly in the valve chamber from one of said openings with its upper 40 end concentric to said valve chamber and forming a valve seat, a gas conducting, or bubbling, tube extending downwardly from the other of said openings into the lower part of said absorption chamber, a spherically true valve member disposed in said valve chamber for cooperation with said valve seat, and said absorption container being of reduced cross sectional area along a substantial length of its lower end surrounding said absorption chamber.
5. A gas absorption pipette comprising an absorption container and an expansion container connected at their lower ends, said absorption container having at its upper end a tubular projection of substantially uniform diameter, a gas 45 inlet tube connected to said tubular projection, a partition wall lying wholly within the container adjacent its upper end and cooperating with said tubular projection to form an upper valve chamber, the lower portion of the container below said wall forming a lower absorption chamber, said wall being provided with a pair of openings, a short tube projecting upwardly from one of said openings to said valve chamber with its upper end concentric thereto, and forming a valve seat therein, a gas 50 conducting or bubbling tube extending downwardly from the other of said openings into the lower part of said absorption chamber, both of said tubes lying wholly within the container, a spherically true valve member disposed in said valve chamber for movement therein and cooperation with said valve seat, and the lower portion of the absorption chamber being of reduced cross sectional area along a length surrounding at least one-half the length of said bubbling tube.
